MACHINE FOR GRINDING CHASERS

Original Filed June 15, 1923 4 Sheets-Sheet 4

UNITED STATES PATENT OFFICE

RALPH E. FLANDERS, OF SPRINGFIELD, VERMONT, ASSIGNOR TO JONES & LAMSON MACHINE COMPANY, OF SPRINGFIELD, VERMONT, A CORPORATION OF VERMONT

MACHINE FOR GRINDING CHASERS

Application filed June 15, 1923, Serial No. 645,515. Renewed June 7, 1929.

This invention relates to a machine for grinding chasers such as are used to cut threads in automatic lathes, screw machines and the like, and provides a construction 5 wherein the chaser and grinding wheel are caused to be relatively traversed to grind the length of the chaser threads and to be automatically fed between such traverses from one to the adjacent thread.

10 For a more complete understanding of this invention reference may be had to the accompanying drawings in which

Figure 1 is a fragmentary front elevation of the machine.

15 Figure 2 is a fragmentary horizontal section on line 2—2 of Figure 1.

Figures 3 and 4 are vertical sections on lines 3—3 and 4—4, respectively, of Figure 2.

20 Figure 5 is a section on line 5—5 of Figure 3, the position of the cam drive shaft being indicated.

Figure 6 is a detail section on line 6—6 of Figure 5.

25 Figure 7 is a fragmentary section on line 7—7 of Figure 5.

Figure 8 is an end view of the machine parts being broken away and the work carrier and related parts removed.

Referring to these figures, 1 indicates a 30 machine base, on the upper face of which is mounted for rectilinear motion a traversing carriage 2, this carriage being supported to slide on suitable guideways 3. In the embodiment shown, at one side of this carriage 35 (Figures 1, 2, 3 and 8) is a substantially cylindrical frame 4 to the end of which is rotatably fixed, as by clamps 5, a disk 6 having a laterally extending arm 7, this disk and arm having bearings 8 for a grinding wheel shaft 9, the angle of which relative to the horizontal may be varied by turning the disk 6 and fixing it in position by means of the clamping bolts 5. This adjustment is not necessary for the purposes of the present invention, the plane of the wheel being vertical at all times but is a feature of a machine which, with some modification, may be employed in the practice of this invention. For an understanding of other advantageous functions 45 of this machine, which however, are not nec-

essary for an understanding of the present invention, reference may be had to my application for patent, Serial Number 564,091, filed May 27, 1922, for grinding machines.

This shaft 9 carries a grinding wheel 10 having its face 11 formed to properly grind the threads of the chaser. Opposite the arm 7 the shaft 9 has fixed thereto a belt pulley 12 over which passes a belt 13 extending

through an opening 14 in the arm 7 to a pulley of a driving motor 15 supported on the frame 4. The frame 4 is permitted a movement toward and from the carriage 2 and transversely of the motion of this carriage so that the wheel may be advanced to cut the work carried by the carriage or be retracted to clear the work.

Extending upwardly from the carriage is a bracket 20 to the upper end of which is pivoted at 21 a bell crank lever 22. This lever has a substantially horizontally disposed arm 23 which at its outer end is pivoted to a vertically arranged slide 24 mounted to slide in a suitable dovetail guideway 25 of the bracket 20, this being shown more particularly in Figure 2. The

forward face of this slide 24 is cut away as at 26 and is so formed as to provide a seat against which the somewhat irregular face 27 of the chaser 28 may bear. The chaser

25 and is so formed as to provide a seat against which the somewhat irregular face 27 of the chaser 28 may bear. The chaser

may be held in position by any suitable means, but as herein shown a clamp bridge 30 is employed extending over the chaser and made fast to the bracket and through this bridge is positioned a set screw 31 having its inner end bearing against the outer face

35 of the chaser. The bell crank lever 22 is oscillated to move the outer end of its arm 23 up and down and so cause a vertical traverse of the chaser. This action may be effected by means of a follower 36 thereon engageable

40 within a cam groove 37 of a cam 38. This cam is fixed to rotate with a shaft 39 extending longitudinally of the carriage and journaled in suitable lugs therein. This shaft 39

45 has fixed thereto a long gear 40 with which meshes a gear 41 mounted to rotate on a stub shaft 42. This gear 41 also meshes with a gear 43 fixed to rotate with a shaft 44 which has loosely journaled thereon a gear 45 having at one end clutch teeth 46 mating with

similar teeth 47 on a clutch member 48 slideable axially of the shaft 44 but rotatable therewith. The gear 45 meshes with a pinion 50 fixed to a shaft 51 and this shaft has a gear 52 meshing with a gear 53 fixed to the main drive shaft 54. This drive shaft extends outwardly of the machine frame whereon it carries any suitable drive mechanism. As herein shown a belt wheel 55 is made fast to this shaft. The shaft 44 also extends outwardly of the machine frame where it has fixed thereto a gear 60 which meshes with a similar gear 61 on a shaft 62. This shaft 62 extends through the machine frame and has fixed thereto at its opposite end, as shown clearly in Figure 1, a worm 65 which meshes with a worm wheel 66 made fast to a cam drum 67. This cam drum 67 carries cams which effect the traverse of the carriage and which also effect a movement of the wheel toward and from the carriage.

The traverse of the carriage is effected by means of a cam disk 70 shown detached in Figure 6, this cam disk having a cam follower 71 bearing thereon, this follower being carried at the lower end of an arm 72 depending from the carriage 2. As shown in Figure 6 this cam is formed with a plurality of arc shaped portions at progressively decreasing distances radially from the axis of the cam drum. The follower 71 is held in engagement with the cam 70 by means of a spring 80 reacting between a portion of the frame in a bracket 81 depending from the carriage. The traversing action of the carriage is merely for the purpose of feeding the chaser so that its several threads may be acted on successively by the grinding wheel, while the cutting traverse lengthwise of the threads is effected by the vertical sliding of the member 24. This cam drum also carries a cam enlargement 75 which acts on one arm 76 of the bell crank lever (see Figures 7 and 8), the other end of this arm engaging at 77 a member 78 having a connection with the frame 4 (see Figure 8). When the high spot of this cam is reached therefore, the member 78 is pushed rearwardly by action of the cam 75 thereon and the wheel is thus pushed backwardly out of contact with the work supported on the carriage, a spring 79 engaging at one end a lug 80 depending from the frame 4 and at its other end fixed to a portion of the frame 1 being employed to urge the wheel forwardly. The action of the mechanism, therefore, is to cause a vertical reciprocation of the slide 24 carrying the chaser therewith so that as the chaser threads are presented to the grinding wheel they are ground to a plane surface lengthwise. After each traverse has been effected in this manner the cam 70 moves to permit the spring 80 to feed the carriage longitudinally to bring the successive threads of the chaser in position to be acted on by succeed-

ing traverses by successive steps. When all the threads have been acted upon in this manner the cam 70 then acts to return the carriage to its former position and at the same time the cam portion 75 acts to retract the grinding wheel so that no cutting strokes are made during this return.

Having thus described certain embodiments of this invention it will be evident to those skilled in the art that many modifications and changes may be made therein without departing from its spirit or scope as defined by the appended claims.

I claim:

1. In a machine of the class described comprising a grinding wheel, a carriage movable substantially parallel to the axis of rotation of said wheel, a chaser holder movable transversely of said carriage to effect relative traversing movement between the cutting face of said wheel and the chaser lengthwise of the threads thereof, means for reciprocating said holder, and means acting automatically between its traverses to move said carriage to cause successive traverses between the wheel and chaser to be effected on adjacent threads.

2. A machine of the class described comprising a grinding wheel, a carriage movable substantially parallel to the axis of said wheel, a slideway on said carriage, a slide movable on said way parallel to the plane of rotation of said wheel, means to clamp a chaser on said slide with its threads extending parallel to its direction of rotation, means for effecting a relative movement of said wheel and carriage to cause said wheel to approach and recede from the threads of the chaser, means to effect sliding of said block to cause said wheel to traverse lengthwise of said threads and means acting between successive traverses to move said carriage to cause successive traverses to effect grinding action on successive threads.

3. In a machine of the class described comprising a grinding wheel, a carriage movable substantially parallel to the axis of said wheel, a slideway on said carriage, a slide movable on said way parallel to the plane of rotation of said wheel, means for clamping a chaser on said slide with its threads extending parallel to its direction of sliding motion, a shaft journaled longitudinally in said carriage, a cam on said shaft, lever connections from said cam for reciprocating said slide on rotation of said shaft, a cam drum having a pair of cam elements thereon, a follower fixed to said carriage in operative engagement with one of said cam elements for causing a step by step motion of said carriage between successive reciprocations of said slide to present the cutting face of said wheel successively to adjacent threads of the chaser, another follower in operative engagement with said other cam element to

1,750,956

advance and retract said wheel toward and from the chaser to cause said wheel to engage and then to clear the chaser, and means for driving said cam and said cam drum in proper timed relation.

5 In testimony whereof I have affixed my signature.

RALPH E. FLANDERS.
